(57) **CLAIM**

The ornamental design for a kettle as shown and described.

DESCRIPTION

FIG. 1 is a front side perspective view of our new design for a kettle.

FIG. 2 is a left side elevation view of FIG. 1.

FIG. 3 is a right side elevation view of FIG. 1.

FIG. 4 is a front side elevation view of FIG. 1.

FIG. 5 is a back side elevation view of FIG. 1.

FIG. 6 is a top plan view of FIG. 1; and,

FIG. 7 is a bottom plan view of FIG. 1.

The broken lines immediately adjacent to the outer perimeter of the base represent the bounds of the claimed design while all other broken lines show portions of the kettle that form no part of the claimed design. The broken lines form no part of the claimed design.

1 Claim, 7 Drawing Sheets
